ARTHUR F. WHITE, OF FULLERTON, CALIFORNIA, ASSIGNOR, BY MESNE ASSIGNMENTS, TO JORDAN & TAYLOR, INC., OF LOS ANGELES, CALIFORNIA, A CORPORATION OF CALIFORNIA

APPARATUS FOR PUMPING WELLS

Application filed August 6, 1928. Serial No. 297,665.

My invention relates to a gas-lift pumping mechanism of novel form, and it is a primary object of this invention to provide a novel apparatus for pumping a well.

In one method of pumping wells it is customary to extend a pipe downward to a point below the surface of the liquid in the well and to introduce a compressed gas either into the lower end of this pipe or into the space above 5 the surface of the liquid, this gas forcing the well liquid in the pipe upward to the surface of the ground. The pressure of this compressed gas is quite high, and with such a pumping mechanism this pressure is transmitted to the liquid-bearing strata of the well, thus tending to impede the inflow of more liquid. In order to allow more liquid to enter the well it is necessary to release the pressure on the liquid-bearing strata, thus necessitating a large waste of compressed gas when 10 the space above the liquid in the well is vented.

It is an object of my invention to provide a gas-lift pumping mechanism wherein the 15 pressure of the compressed gas cannot reach the liquid-bearing strata.

A further object of my invention is to provide a gas-lift pumping apparatus in which the differential pressure between the liquid-bearing strata and the interior of a well-casing 20 may be regulated.

I have found that a very efficient pumping action takes place when a compressed gas is intermittently supplied to a chamber at least 25 partially submerged in the well liquid, this gas pressure closing the liquid-intake valves of the chamber and forcing the liquid entrapped in the chamber upward through a delivery pipe which extends into the chamber. A check valve prevents any return flow 30 of liquid through the delivery pipe. Furthermore, I have found it advantageous to vent the chamber to the exterior of the pumping mechanism when the gas has been shut off and a new supply of liquid is entering 35 the chamber.

It is an object of my invention to provide a chamber situated at least partially below the liquid level of a well and adapted to 40 trap a body of liquid therein, this liquid be-

ing displaced by a compressed gas supplied to the chamber from the surface of the ground.

A further object of my invention is to position a gas-intake valve situated adjacent such a chamber, and controllable from the 55 surface of the ground to supply a compressed gas to the chamber.

Still a further object of my invention is to provide a vent for such a chamber, which is closed when the gas-intake valve is open, and 60 compressed gas is entering the chamber, but open when a new supply of liquid is entering the chamber.

Still another object of my invention is to provide a novel arrangement of tubing 65 for supporting a gas-lift pumping mechanism and for supplying compressed gas thereto and conducting the pumped liquid therefrom.

Referring to the drawings, in which I illustrate a preferred embodiment of my invention:

Fig. 1 is a vertical sectional view illustrating the utility of my invention and showing the gas-intake valve thereof in closed position.

Fig. 2 is a sectional view taken on the line 2—2 of Fig. 1.

Fig. 3 is a sectional view taken on the line 3—3 of Fig. 2 and illustrating the valve in 80 another position.

Fig. 4 is a view taken on the line 4—4 of Fig. 3.

Fig. 5 is a view taken on the line 5—5 of Fig. 3.

Referring particularly to Fig. 1, I illustrate a well 10 in which a well-casing 11 has been set, this well-casing preferably extending downward to the liquid-bearing strata of the well indicated by the numeral 12, and being perforated adjacent these strata. The upper end of the casing 11 is closed by a head 13, and the pressure inside the casing is regulated by a valve 14 placed in a pipe 15 communicating with the interior of the casing. This pressure may be registered on a gauge 16.

Extending downward through the head 13 is a primary tubing 20, the lower end of which is preferably a short distance above 100

the liquid level normally present in the well, this liquid level being indicated by the line A—A of Fig. 1. Threaded to the lower end of this primary tubing is a chamber structure 22 having a head member 23 in which a bore 24 is formed in a manner to communicate with the interior of the tubing 20. The lower end of the bore provides a seat 25 in a groove of which an annular packer 26 is retained in a manner best shown in Fig. 3.

10 The conical face of a plug member 28 is adapted to engage the annular packer 26, this packer being adapted to maintain a fluid-tight engagement between the plug member 28 and the head member 23.

15 A secondary tubing 30 is threadedly received by the upper end of the plug member 28 and at least partially supported thereby, this tubing extending upward through the 20 primary tubing and through a head 31 thereon, being capped at its upper end by a head 32 communicating with an outlet pipe 33. Compressed gas is adapted to be intermittently supplied to an annular intake space 25 35 between the primary and secondary tubing through a pipe 36 communicating with the head 31. This intermittent flow of gas is regulated by any suitable mechanically or electrically operated valve mechanism 37 of 30 such a type that the time interval of gas flow through the annular space 35 may be readily varied, as well as the time between successive gas flows therethrough.

35 The lower end of the head member 23 is threaded to receive a shell 40, which is closed at its bottom and forms a part of the chamber structure 22, this shell and the head member 23 cooperating to form a pumping chamber 41 which may be relatively long and extend through a considerable proportion of 40 the distance between the liquid level A—A and the lower portion of the well 10 if so desired. I prefer to position the chamber 41 so that it lies almost completely below the 45 surface A—A, but my invention will operate as long as the chamber 41 is at least partially submerged in the well liquid.

50 This chamber is adapted to receive well liquid through liquid-intake valves 42 situated near the lower end of the chamber. I have illustrated these valves as being of the flapper type but it should be understood that I am not limited thereto. Any form of valve, 55 which will admit liquid into the chamber 41 and prevent an outward flow, will serve the purpose.

50 The interior of the secondary tubing 30 communicates with the chamber 41 through a bore 43 formed centrally through the plug member 28, and an opening 44 formed through the head member 23. The opening 44 is axially aligned with the bore 43, the lower end thereof being threaded to receive a delivery tube 45, which extends downward 65 through the chamber 41 to a position near the

lower end thereof. The lower end of the delivery tube 45 carries a seat 46 in which a ball 47 is adapted to normally rest, this ball being displaced upward in a cage 48 when liquid is rising in the delivery tube 45. The seat 46 and ball 47 cooperate to form a check valve to prevent any flow of liquid from the delivery tube 45 into the chamber 41.

70 As the well liquid is entering the chamber 41, it is desirable to vent the upper end of this chamber to the exterior of the head member 23. This I accomplish by means of vent openings 50, best shown in Fig. 3. These openings preferably communicate with the space above the liquid level A—A, but this arrangement is not necessary to my invention, inasmuch as any gas passing through the vent openings 50 will rise in the well fluid surrounding the head member 23 should the level A—A be above the openings 50.

75 An intake passage 53 is formed in the head member 23 and communicates at the one end with the annular space 35, the other end of this passage communicating with a valve chamber 54, there being a conical seat 55 formed at the point where the passage 53 opens on the valve chamber 54. The lower end of the valve chamber communicates with the pumping chamber 41.

80 Adapted to slide in the passage 53 is a stem 56 of a gas-inlet valve 57, which forms a fluid-tight fit therein until this valve is lowered a sufficient distance so that the bottom of a notch 59 enters the valve chamber 54, at 85 which time compressed gas may flow from the annular space 35 through the passage 53 and into the pumping chamber 41 through the valve chamber 54. A head 60 is formed on the gas-intake valve 57 and is journaled in the valve chamber 54, this head having 90 passages 61 allowing the compressed gas to pass. The upper end of the head 60 is provided with a conical face 62, which is adapted to engage the seat 55, thus determining the 95 uppermost position of the gas inlet valve 57.

100 Adapted to slide in the lower end of the valve chamber 54 is a plunger 65, there being 105 passages 66 formed in the periphery thereof to allow the compressed gas to enter the pumping chamber 41. The head 60 and the plunger 65 are separated by a spring 67, this 110 spring being of such a length that the maximum separation of the head and the plunger takes place when the mechanism is in a position indicated in Fig. 3.

115 The lower end of the plunger 65 bears against a ball 68, held in a pocket 69 of a valve member 70, which is formed of a shape best 120 shown in Figs. 1, 2, and 3. This valve member has an opening 72 through which the delivery tube 45 passes, and pins 73 journal 125 this valve member so that it may be pivoted about an axis B—B passing through the axis of the delivery tube 45, so that the valve 130

member may be moved from a position shown in Fig. 1 into a position shown in Fig. 3.

Such a movement takes place when the valve 37 allows the compressed gas to enter the annular space 35 and build up a pressure against the stem 56 of the gas-intake valve 57. This pressure is resisted by a spring 75 positioned in a bore 76 extending upward into the head member 23, this spring bearing 10 against a piston 77 which in turn is operatively connected to the valve member 70 by a ball 78. As will be apparent in the drawings, the bore 76 is on the opposite side of the head member 23 from the valve chamber 54, so that as the gas pressure on the stem 56 builds up, the spring 75 is compressed, due to the fact that this spring is more easily compressed than the spring 67. The valve member 70 thus moves into a position indicated in 20 Fig. 3, at which time the lower end of each vent opening 50 is closed by a ball 80 held in a cup 81 of the valve member 70. An opening 82 communicates with the cup 81 and prevents any excess or deficiency of pressure in this cup. The effective areas of the piston 77 and plunger 65 are preferably equal so that any pressure which builds up in the chamber 41 acts equally on these members. The valve member 70, together with the parts 25 mechanically connected thereto and adapted to control the passage of gas to and from the chamber 41, forms a pressure-operated valve operable from the surface of the ground.

When the mechanism is in this position, the 30 bottom of the notch 59 has not quite reached the valve chamber 54, so that no gas escapes from the annular space 35 into the pumping chamber 41. When the gas in this annular passage becomes great enough to overcome 35 the action of the spring 67, the gas intake valve 57 lowers against the action of the spring 67 and compressed gas enters the upper end of the pumping chamber 41. Any well liquid in this chamber is entrapped 40 therein due to the valves 42 preventing any of the liquid from escaping into the casing 11. The gas pressure thus built up in the upper end of the chamber 41 forces the liquid downward in this chamber, this liquid 45 rising in a discharge passage 85, formed by the delivery tube 45, the opening 44 and bore 43, and the secondary tubing 30 to the surface of the ground and being discharged through the outlet 33.

50 When the valve mechanism 37 operates to shut off the supply of compressed gas, the spring 67 expands, thus bringing the bottom of the notch 59 above the valve chamber. The spring 75 now operates to throw the valve member into its position shown in Fig. 1, thus uncovering the vent openings 50 and allowing the upper end of the chamber 41 to be vented therethrough so that a new supply 55 of oil may enter the pumping chamber 41 due

to the pressure head between the surface A—A and the liquid intake valves 42.

The liquid rises in the chamber 41 until it reaches a level substantially the same as the liquid level A—A of the well, or until the chamber is completely filled in the event that this chamber is completely submerged. During this rise of liquid the gas thereabove is forced through the vent openings 50. It should be understood that the spring 75 acts 75 to hold the valve mechanism in the position shown in Fig. 1 until the timing mechanism 37 acts to again supply a compressed gas to the annular space between the primary and secondary tubing. When the pressure difference between the annular space 35 and the interior of the chamber 41 again reaches the predetermined value the series of operations above outlined is repeated.

There are several possible methods of operating my invention by regulating the timing mechanism 37. I prefer, however, to so adjust this mechanism that the chamber 41 will be substantially completely filled with well liquid before the compressed gas actuates the valve mechanism. Furthermore, I prefer to lower the liquid level in the chamber 41 to a point below the seat 46, so that a column of gas enters the discharge passage 85. In the latter event, it is necessary to attach the outlet pipe 33 to a suitable separator for separating the gas and liquid. Such separators are well-known in the art and do not form a part of this invention.

I have found such a method of procedure 100 particularly applicable to the pumping of an oil well. All oil, as it is taken from the ground, contains therein certain entrained gases which are liberated when the pressure on the oil is reduced. As a slug of oil passes 105 upward through the discharge passage 85, the pressure thereon becomes less as this oil nears the surface of the ground. This slug of oil thus becomes more buoyant during the upper portion of its travel, and by a proper regulating of the timing mechanism 37 it is 110 possible to obtain a maximum oil output per unit volume of gas.

It should be understood, however, that I 115 am not limited to this mode of operation, inasmuch as the timing mechanism 37 may be so regulated that no compressed gas reaches the discharge passage 85, at which time this passage will be entirely filled with liquid instead of having alternate slugs of liquid and gas throughout its length. So also, the timing mechanism 37 may be regulated to supply compressed gas until the body of liquid entrapped in the chamber 41 is completely expelled from the well, although this mode of 120 operation gives poor efficiency.

It should further be noted that the pressure of the compressed gas is not transmitted to the liquid-bearing strata 12. Thus, there 130 will be no tendency for the liquid to be forced

into the strata each time the pumping mechanism operates.

Furthermore, it is often desirable to control the differential pressure between the interior of the casing and the liquid-bearing strata 12. This may readily be accomplished by controlling the pressure inside the casing 10 by means of the valve 14. When a well is comparatively new, the normal differential pressure between the interior of the casing and the liquid-bearing strata is very high, and if this differential pressure is reduced, the producing life of the well is materially lengthened. It is thus an important feature 15 of my invention that this differential pressure may be controlled by regulating the amount of pressure in the casing 11.

The particular construction of valve mechanism illustrated is not claimed per se in this 20 application, any pressure-operated valve which simultaneously opens the passage 53 and closes the vent openings 50 being equally applicable to the pumping mechanism shown. Furthermore, any valve which performs these 25 functions and which is situated in the lower end of the well and which is controllable from the surface of the ground might be utilized. The particular valve illustrated is operated from the surface of the ground merely by 30 building up the pressure in the annular space 35, but electrically or mechanically operated valves might be substituted, these valves being operable from the surface of the ground.

The particular arrangement of tubing illustrated is another important feature of my 25 invention, inasmuch as it is compact in design and gives the advantages above outlined relative to the regulation of differential pressure and prevention of high pressure against the 40 liquid-bearing strata of the well.

The particular arrangement of tubing and pumping mechanism shown is also extremely valuable in increasing the pumping efficiency, for it should be clear that it is not necessary 45 to waste a large per cent of the gas in reducing the pressure sufficiently to allow liquid to enter the casing as is necessary in the ordinary form of gas-lift pump. I have found that the cost of lifting a unit volume of liquid 50 is only a small fraction of the normal lift cost of other types of gas-lift and mechanically reciprocating pumps.

I have found the particular means of joining the plug member and the head member to be advantageous in forming a tight joint between these members, due to the fact that the 55 packer 26 may be made to carry a portion or all of the weight of the primary tubing 20, thus insuring a fluid-tight joint between the 60 members 23 and 28.

I claim as my invention:

1. In a displacement pump for pumping wells having a pump chamber formed therein, a compressed gas controlling valve comprising a valve body or head member includ-

ing an intake passage communicating with a compressed gas supply, a valve chamber central with and communicating with said intake passage and communicating with the pumping chamber, a valve seat formed at the junction of said intake passage and said valve chamber; a gas inlet valve operatively mounted in said valve chamber and including a stem arranged to form a piston in said intake passage, a notch extending for a portion of the length of said stem, said notch arranged to permit the flow of compressed gas past said valve when said valve has moved a predetermined distance, and a valve head having a valve seat arranged to contact said valve body inlet passage seat and having gas passages positioned upon its periphery, a plunger slidably mounted in said valve chamber and having gas passages positioned upon its periphery, an inlet valve spring positioned between said gas inlet valve and said plunger, a plurality of vent passages communicating between said pumping chamber and the exterior of said displacement pump, and having valve seats; a plurality of vent passage valves, a valve member carrying said vent passage valves and engageable with said plunger, means pivotally mounting said valve member on said valve body for movement by displacement of said plunger to close said vent passages and a second spring means normally biasing said valve member to open said vent passages until the compressed gas pressure exceeds a predetermined value and displaces said inlet valve 100 and said plunger.

2. In a displacement pump for pumping wells having a pumping chamber therein, a compressed gas controlling valve comprising a valve body including an intake passage 105 communicating with a compressed gas supply, a valve chamber central and communicating with said intake passage and communicating with the pumping chamber, a valve seat formed at the junction of said intake passage and said valve chamber; a gas inlet valve operatively mounted in said valve chamber and including a stem arranged to form a piston in said intake passage, and arranged to move a predetermined distance 110 before opening said inlet passage, and a valve head having a seat arranged to contact said valve body inlet passage seat; a plunger slidably mounted in said valve chamber, an inlet valve spring positioned between said gas inlet valve and said plunger, a vent passage having a valve seat, a vent passage valve, a valve member carrying said vent passage valve and engageable with said plunger, means pivotally mounting said valve member on said valve body for movement by displacement of said plunger to close said vent 115 passages and a second spring means normally biasing said valve member to open said vent passages until the compressed gas pressure 120 exceeds a predetermined value and displaces said inlet valve and said plunger.

130

exceeds a predetermined value and displaces said inlet valve and said plunger.

3. In a displacement pump for wells having a pumping chamber therein, a compressed gas controlling valve comprising a valve body including an intake passage communicating with a compressed gas supply, a valve chamber central and communicating with said intake passage and communicating with the pumping chamber, a valve seat formed at the junction of said intake passage and said valve chamber; a gas inlet valve operatively mounted in said valve chamber and including a stem arranged to form a piston in said intake passage, and arranged to move a predetermined distance before opening said inlet passage, and a valve head having a seat arranged to contact said valve body inlet passage seat; a plunger slidably mounted in said valve chamber, an inlet valve spring positioned between said gas inlet valve and said plunger, a vent passage having a valve seat, a vent passage valve, a valve member pivotally mounted in said valve body and arranged to operatively contact said plunger and to operatively carry said vent passage valve, whereby when said valve member is in one position said vent valve is open and said inlet valve closed; and means for resiliently holding said valve member in position to open said vent passage.

In testimony whereof, I have hereunto set my hand at Los Angeles, California, this 22nd day of June, 1928.

ARTHUR F. WHITE.
